UNITED STATES PATENT OFFICE

104,995

DESIGN FOR A COMBINED FLOWERPOT AND SUPPORT

Frank Lee Devereux, Jacksonville, Tex.

Application February 23, 1937, Serial No. 67,815

Term of patent 3½ years

To all whom it may concern:

Be it known that I, Frank Lee Devereux, a citizen of the United States, residing at Jacksonville, in the county of Cherokee and State of Texas, have invented a new, original, and ornamental Design for a Combined Flower Pot and Support, of which the following is a specification, reference being had to the accompanying drawing, forming part thereof.

I claim:—

The ornamental design for a combined flower pot and support as shown.

FRANK LEE DEVEREUX.
